SKI BINDING

Ole Miöen, Stockholm, Sweden

Application January 14, 1939, Serial No. 251,008
In Sweden January 17, 1938

4 Claims. (Cl. 280—11.35)

My present invention relates to ski bindings and has for its object to provide a ski binding which is of simple, reliable and cheap construction and which can be put on and removed from the foot in the simplest possible manner without the need of loosening any fore-bindings.

The invention resides essentially in the provision, in a ski binding, of a spring (spiral, leaf, wire or similar spring) which is straight or practically straight in its unstretched condition and is adapted to serve as a support for the rear part of the heel of the shoe, said spring being arranged to be attached to the ski by suitable means, e. g. adjustable bindings (straps, iron bands, wires etc.), or to a toe support attached thereto, in such manner that when fastening the ski binding around the foot the bending tension of the spring will be utilized in the first instance.

The attached drawing shows one embodiment of a ski binding according to this invention, Figure 1 showing a side view of the middle part of a ski with a ski binding attached thereto, Figure 2 a top view thereof and Figure 3 a cross section of the heel iron.

On the drawing 1 designates the ski and 2 a toe iron of ordinary construction. For attachment around the heel of the shoe there is provided, in the shown embodiment, a special heel iron 3 having a bent profile, as may be seen in Figures 1 and 3, so that on the outside a guide or seat is formed for a spiral spring 4 which is straight in its unstretched position. As will be seen from Figure 1, the upper arc of the curved profile of the heel iron is made somewhat larger than the lower one in order to facilitate the insertion of the heel of the shoe in the aforementioned iron.

Attached to the ends of the spring are iron bands or runners 5 formed at the free ends of the heel iron 3. The runners 5 are shaped to form at their free inner ends fasteners 7 for straps 8 which are attached in suitable manner to the ski under the toe iron 2, or alternatively they may be fastened to this iron. The fastenings of the straps are, as shown in Figure 1, made wider than the running iron 5 so that a stop 9 is formed against which the inner ends of the guides 6 provided on the heel iron will come to rest under the influence of the spring tension when the foot is removed from the binding. At the inside of the heel iron 3 is a bulge 10 formed, for instance, by pressing and intended to engage with the groove usually found in the heel of sports shoes, thus fixing the position of the heel iron.

When putting on the binding, which is done by inserting the foot into the toe iron 2 and tramping down into the heel iron 3, the spring 4 is automatically stretched through the heel iron 5 being brought back from its rest against the stop 9. By suitably adjusting the length of the running irons 5 reckoned from the spring support to the aforementioned stop, the spring 4 can be given a suitable preliminary tension before the actual load tension sets in because of the tramping down into the heel iron.

By the arrangement described above an effective ski binding is obtained in as much as the foot is always kept pressed against the toe-iron 15 with a spring tension which can be regulated beforehand within a wide margin. If, for instance, a spiral spring is used as shown in the drawing, said spring may be of ordinary standard make. It can be made from heavy wire so that the spring becomes strong and reliable. The spring need not thereby become too stiff, in that not only the bending tension set up in the spring because of the bending of the spring against the heel iron may be utilized, providing a very soft 25 springiness, but also the hard tension when the spring is stretched longitudinally in the usual manner. By this means it is thus possible to obtain a more ideal springiness by means of a cheap standard spring than that obtained even by an expensive special spring.

Moreover, all special tightening means are eliminated. The usual tension in the straps develops, after the binding has been adjusted to its correct length in relation to the foot, simply 35 by tramping down against the heel iron. The foot can be freed from the binding by jerking up the heel while the heel iron is held against the ski with the other foot.

The straps 8 may be fastened to the ski either 40 under the toe-iron, as shown in the figures, or be attached in the usual manner to the toe-iron by means of joints. In the first case the straps will lay themselves against the sole of the shoe when bending the foot whereby the foot is held even more firmly to the ski. Furthermore, by fastening the straps under the toe-iron the heel 45 will be drawn downwards against the ski, the foot being thereby held more firmly than by a fastening to the toe-iron.

The strap 8 can be joined with the spring 4 either by being inserted through pressed slits in the runners 5, 7, as is shown in the figures, or in some other manner, e. g. by having the end of the runner supporting an ordinary buckle. Thanks to the resiliency provided the tension in

the straps can be reduced considerably as compared with non-resilient bindings without reducing the firmness of the hold of the foot. Naturally, the life of the strap is hereby prolonged. By the arrangement shown a further assurance is had against too great a tension in the strap because it is possible so to adjust the conditions by suitably dimensioning the holes in the runners that the strap will slide in the runner if the strap tension should become too great.

Naturally, a ski binding according to this invention comprising a spring which is straight or practically straight in its unstretched state can be made without a special heel iron, in which case the spring will rest directly against the heel. If in such a case no special heel iron is provided, the inside portion of the spring may be equipped with a bulge or something similar which fits into the groove in the heel of the shoe. The straps may also be replaced by rods, irons, et cetera which may be joined in a suitable manner with the ski or toe-iron respectively.

I claim:

1. A ski binding comprising a toe piece adapted to receive the toe of a boot and a heel grip adapted to hold the boot firmly in said toe piece, said heel grip comprising two side members extending along the sides of the boot and a rear member connecting together the rear ends of said side members, said rear member consisting of a stiff helical spring of substantially the same length as the width of the heel and extending substantially transversely of the ski and adapted to be subjected to a transversal bending action when acted upon by the boot during skiing.

2. A ski binding comprising a toe piece adapt-

ed to receive the toe of a boot and a heel grip adapted to hold the boot firmly in said toe piece, said heel grip comprising two side members extending along the sides of the boot, a rear member connecting together the rear ends of said side members, and consisting of a stiff helical spring of substantially the same length as the width of the heel and extending substantially transversely of the ski and adapted to be subjected to a transversal bending action when acted upon by the boot during skiing, and a heel iron shaped to fit the heel of the shoe and forming a bearing for said spring.

3. A ski binding comprising a toe piece adapted to receive the toe of a boot and a heel grip adapted to hold the boot firmly in said toe piece, said heel grip comprising two side members extending along the sides of the boot, a rear member connecting together the rear ends of said side members, and consisting of a stiff helical spring extending along its whole length substantially transversely of the ski and adapted to be subjected to a transversal bending action when acted upon by the boot during skiing, a pair of rigid iron straps forming the rear portions of said side members, and a heel iron forming a bearing for said spring and being slidable longitudinally on said straps.

4. A ski binding as claimed in claim 3, in which the heel iron is slidable rearwardly on the straps from a forward end position in which the heel iron engages with stop abutments on the straps under the action of an initial bending tension in the spring.
